UNITED STATES PATENT OFFICE.

FRANK O. WORTHLEY, OF BOSTON, MASSACHUSETTS.

DESIGN FOR A FEEDING-MANGER.

SPECIFICATION forming part of Design No. 19,686, dated March 4, 1890.

Application filed February 28, 1887. Serial No. 229,203. Term of patent 3½ years.

To all whom it may concern:

Be it known that I, FRANK O. WORTHLEY, a citizen of the United States, residing at Boston, in the county of Suffolk and State of Massachusetts, have invented and produced a new and original Design for Feeding-Mangers, of which the following is a specification, reference being had to the accompanying illustration, forming part thereof.

5 The illustration herewith annexed represents a feeding-manger, showing my design in front elevation.

10 The leading feature of my design consists in a horizontal bar having two pendent parts at either extremity and a central upraised part.

15 A represents the central rising bulbous por-

tion; B, the pendent hat-shaped hollowed-out portion; C, the pendent cup-shaped part at the opposite end of the horizontal bar, which is designated at D.

What I claim is—

The design for feeding-mangers, as herein shown and described, the same comprising the upraised bulbous-shaped part A, the horizontal bar D, the hat-shaped piece B, and the cup-shaped part C, the parts B and C being respectively pendent from the opposite ends of the horizontal bar D, as specified and set forth.

FRANK O. WORTHLEY.
